UNITED STATES PATENT OFFICE.

JOHN DUNDON, OF CORK, IRELAND.

COIN-CONTROLLED RACE GAME.

SPECIFICATION forming part of Letters Patent No. 663,159, dated December 4, 1900.

Application filed August 31, 1899. Serial No. 729,067. (No model.)

To all whom it may concern:

Be it known that I, JOHN DUNDON, a subject of the Queen of Great Britain, residing at 11 Glenview Terrace, Ballyhooly road, Cork, 5 Ireland, have invented new and useful Improvements in or Connected with Race Games and Coin-Freed Mechanism for Use in Connection Therewith, of which the following is a specification.

10 My invention relates to a race-game wherein in the competing figures are mounted on endless belts or chains carried upon a series of pulleys or wheels adapted to be independently operated by two or more persons playing the game, means being provided whereby the competing figures will be allowed to go a limited number of laps or rounds for a coin of given value.

In carrying out my invention I mount the 20 pulleys or wheels carrying the belts or chains on shafts provided with handles whereby they can be operated, and I provide a plate or catch extending across the race-table at a right angle to the said belts or chains and beneath the upper portions thereof. The plate is heavier at one side of its pivot than at the other, so that normally one edge engages with projections on the belts and prevents them being moved. In order to disengage the plate 25 from the belts I provide a lever connected at one end to the plate or catch, the free end of the lever being provided with the receptacle or cage for the reception of a coin. By placing a coin in the receptacle or cage the lever 30 will be moved and disengage the plate or catch from the belts or chains. To dislodge the coin from the receptacle or cage I provide a shaft having a crank or eccentric. This shaft is provided with pulley or chain 35 wheels connected to it by ratchet mechanism and engaging the belts or chains hereinbefore described. The crank or eccentric operates a driving-catch which engages a toothed wheel, the latter being provided with a pivoted arm which as the toothed wheel revolves 40 comes into contact with a lever on the money-cage, which arm dislodges the coin from the said cage and allows the cage-lever to move the plate or catch, hereinbefore described, 45 into the path of the projections on the belts or chains.

In some cases I pivot the coin-receptacle

so that when moved by the weight of a coin it will, by coming into contact with an obstacle, discharge the coin. As this arrangement, 55 however, would allow of the premature return of the cage to its normal position, I provide the cage-lever at its free end with a jointed leg which when the lever is moved by the coin will assume a vertical position and support the cage-lever until moved away by a projection on a belt or chain moved by one of the operators.

To enable my invention to be fully understood, I will describe how it can be carried 65 into practice by reference to the accompanying drawings, in which—

Figure 1 is a longitudinal section of race-game apparatus constructed according to my invention and designed for use by four players. Fig. 2 is a horizontal section of part of the same. Fig. 3 is a section on the line 3 3, Fig. 1, drawn to a larger scale. Fig. 4 is a section on the line 4 4, Fig. 3. Fig. 5 is a view of the coin-cage and the means for dislodging the coin therefrom, also drawn to an enlarged scale. Fig. 6 is a longitudinal section of my modified form of apparatus and designed for use by two players. Fig. 7 is a section on the line 7 7, Fig. 6, drawn to a 80 larger scale. Fig. 8 is a view drawn to an enlarged scale, illustrating the supporting-lever for the coin-cage lever.

Similar reference-letters indicate corresponding parts throughout the drawings. 85

a is the case of the apparatus, and *b b* are the belts or chains carrying the competing figures *c c*, which chains pass around wheels *d d*, operated by the handles *e e* through the medium of the shafts *f f*. There are as many 90 of the shafts *f f* as there are competing figures, and consequently a like number of chains. In the construction shown in the drawings there are four of the shafts *f f*, each of which is provided with three loose sprockets and one fixed sprocket-wheel, the fixed sprocket-wheel of each shaft being situated opposite to a loose sprocket on one of the shafts at the other end of the case *a*. It will be readily seen that each competing figure 100 will be operated separately from the others by means of the handles above referred to.

g is the pivoted plate or catch extending across the race-table at a right angle to the

belts or chains b and weighted at one end, as at g' , so that the other end can engage with projections b' on each of the belts.

h is the lever carrying at one end the coin-receptacle h' and connected at the other end by a link h^2 to the plate or catch g . By inserting a coin through the slot a' in the case a it will pass into the receptacle h' and move the lever h and plate or catch g from the position shown in full lines to that shown in dotted lines in Figs. 1 and 6—that is to say, it will disengage the said plate or catch from the projections b' on the belts b . The belts are now free to be moved by the handles $e e$.

15 In order that the competing figures shall only be moved a certain number of laps for each competition, I provide for keeping the lever h in the dotted position, and consequently the plate or catch g out of engagement with the projections b' , until the last lap is being performed. This is effected in the arrangement shown in Figs. 1 to 5 by retaining the coin in the receptacle h' until this time, so as to hold the parts in position. For dislodging the coin during the last lap the shaft i is provided, having pulley or chain wheels $j j$, with which engage the belts or chains $b b$, each of the said pulleys or chain-wheels being mounted loosely on shaft i and provided with 25 a pawl j' , engaging with a ratchet-wheel j^2 on the shaft i , as shown in Figs. 3 and 4. This ratchet mechanism, while allowing the positive movement of the shaft i by any one of the wheels j , yet allows of their independent 30 movement due to the different speeds at which the belts or chains may be actuated by the operators, as will be obvious. It will thus be seen that the shaft i will always be driven by the most rapidly-moving wheel j .

40 k is the eccentric (or crank) on the shaft i , and l the driving-catch operated thereby and engaging the toothed wheel m .

n is the pivoted arm on the wheel m , which is weighted to cause it to normally assume a vertical position and during the last lap comes into contact with one end of the lever o , pivoted on the coin-receptacle, (the other end of which projects within the receptacle behind the coin, as indicated in Fig. 5,) and moves 45 it so as to dislodge the coin from the said receptacle into the drawer p , the lever h and plate g then returning to their normal positions under the influence of the weight g' . By having the arm n pivoted it assumes a 50 more or less angular position when operating the lever o , due to the resistance of the latter, and when the coin is dislodged the arm again assumes a perpendicular position to the left of the lever o , so that the next time the coin-receptacle descends with a coin the arm n 55 cannot come into contact with the said lever until the wheel m has made nearly another revolution.

60 m' is a detent-pawl for preventing any backward movement of the wheel m .

In the arrangement illustrated in Figs. 6, 7, and 8 the coin-receptacle h' , which is in the

form of a platform for the coin to lie on, is pivoted to the lever h , so that as it descends under the weight of the coin an angular projection q on its underside impinging against a pin r causes the receptacle h' to turn on its pivot and discharge the coin down a chute s into the drawer p . t is the leg which I joint to the free end of the lever h , which leg when the lever is moved by the coin assumes a vertical position due to its weight, as shown by the dotted lines in Fig. 6, and supports the lever h on a platform u until moved away by a projection v , Fig. 8, on a belt or chain 80 w , running on pulleys or chain-wheels w' . The belt or chain w is actuated from one of the shafts f through the medium of pulleys or wheels $x y$ and belt or chain z .

b^2 is a detent or catch against which the 85 projections b' will impinge and be stopped if the belts or chains be moved backward.

In order to avoid damage to the parts when the projections b' on the belts or chains b come against the plate or catch g , I arrange the connection between the operating-handles $e e$ to be a frictional one, so that the handles can be moved, although the belts or chains are held stationary. This I effect by arranging the said handles free on the shafts $f f$ and providing them with springs e' , Fig. 2, which bear against disks e^2 , fixed to the said shafts. The pressure of the springs can be adjusted by nuts e^3 , screwing on the shafts f .

Although I have shown the plate or catch 100 g arranged to engage with the belts or chains carrying the competing figures, it will be obvious that I can arrange it to engage with parts in operative connection with the said belts or chains.

Having now particularly described and ascertained the nature of my said invention and in what manner the same is to be performed, I declare that what I claim is—

1. In apparatus for playing a race game the 110 combination of endless belts or chains, figures carried thereby, pulleys or wheels carrying the belts or chains, means for enabling two or more persons to impart independent movement to the belts or chains, means for normally locking the belts or chains against movement in one direction and coin-free mechanism for disengaging the said locking means, substantially as described.

2. In apparatus for playing a race game the 120 combination of endless belts or chains, figures carried thereby, pulleys or wheels carrying the belts or chains, means for enabling two or more persons to impart independent movement to the belts or chains, a weighted plate 125 or catch for normally locking the belts or chains against movement in one direction and coin-free mechanism for removing the plate or catch from the belts or chains, substantially as described.

3. In apparatus for playing a race game the 130 combination of endless belts or chains, figures carried thereby, pulleys or wheels carrying the belts or chains, means for enabling two

or more persons to impart independent movement to the belts or chains, a weighted plate or catch for normally locking the belts or chains against movement in one direction, a lever, connected to the plate or catch and a coin-receptacle carried by the said lever, substantially as described.

4. In apparatus for playing a race game the combination of endless belts or chains, figures carried thereby, pulleys or wheels carrying the belts or chains, means for enabling two or more persons to impart independent movement to the belts or chains, means for normally locking the belts or chains against movement in one direction, a lever connected to the plate or catch, a coin-receptacle carried by the said lever and means whereby the belts or chains are not locked till the said figures have gone a predetermined number of laps, substantially as described.

5. In apparatus for playing a race game, the combination of endless belts or chains, figures carried thereby, pulleys or wheels carrying the belts or chains, means for enabling two or more persons to impart independent movement to the belts or chains, a plate or catch for normally locking the belts or chains against movement in one direction, a lever connected to the plate or catch, a coin-receptacle carried by the said lever, additional pul-

leys or chain-wheels engaging the belts or chains, a shaft carrying them, ratchet mechanism for operating the shaft from the said pulleys or wheels, an eccentric or crank, a driving-catch operated by the eccentric or 35 crank, a toothed wheel operated by the driving-catch, a weighted arm on the toothed wheel and a lever on the coin-receptacle for discharging the coin, substantially as described.

40 6. In apparatus for playing a race game, the combination of endless belts or chains, figures carried thereby, pulleys or wheels carrying the belts or chains, means for enabling two or more persons to impart independent movement to the belts or chains, means for normally locking the belts or chains against movement in one direction, a lever connected to the plate or catch, a coin-receptacle pivoted to the said lever, a pin against which the 45 receptacle impinges and is tipped to discharge the coin, a leg at one end of the lever and a traveling belt or chain having a projection thereon operated from one of the handles, substantially as described.

JOHN DUNDON.
